UNITED STATES PATENT OFFICE

PERRY D. HUSHOUR, OF YOUNGSTOWN, OHIO, ASSIGNOR TO WALTER M. CHARMAN,
OF YOUNGSTOWN, OHIO

VALVE SEAT

Application filed December 17, 1929. Serial No. 414,707.

The present invention relates broadly to the art of fluid distribution and control, and more particularly to a seat for valve structures of the character utilized, for example, for open hearth furnace sewers. Such seats have been formed in the past either by casting or welding structural plates together in order to form a comparatively large passageway for the circulation of cooling water. Such structures necessarily provide portions of widely different cross sectional areas in the path of water circulation. As a result, the water flowing therethrough is subjected to changes in velocity. Each time the velocity of flow decreases to any appreciable extent, there is a tendency to deposit dirt, sludge, and other foreign matter which may have been in the water stream. This results, in a comparatively short time, in an appreciable accumulation on the inside of the seat, usually more or less localized. Such accumulation forms a good insulator and does not permit heat to be taken away as rapidly from such insulated portion as from the remaining portions. This necessarily causes uneven expansion and contraction in the valve seat and consequent cracking or warping thereof.

In accordance with the present invention, there is provided an improved construction possessing not only desirable attributes from the standpoint of simplicity, cost, and relatively light weight, but also from the standpoint of ability to provide effective and substantially uniform water cooling throughout all portions thereof. When it is considered that in the open hearth practice, the sewers are called upon to handle gases well above 2000° F., the necessity for efficient and uniform water cooling will be appreciated.

In the accompanying drawings there are illustrated certain preferred forms of my invention.

In the drawings:

Figure 1 is a front elevational view of the seat itself.

Figure 2 is a side elevational view of the structure illustrated in Figure 1.

Figure 3 is a side elevational view showing the seat in position and in cooperative engagement with a valve, and

Figure 4 is a view similar to Figure 1, illustrating a modified embodiment of the invention.

In accordance with the embodiment of the invention illustrated in Figures 1, 2 and 3 of the drawings, the seat comprises an inner substantially paddle shaped or looped portion 2 with an outer portion 3 similarly shaped and substantially uniformly spaced therefrom throughout the entire periphery. As will be readily apparent from Figure 2 of the drawings, the inner and outer portions lie in substantially the same plane throughout the entire length. The inner portion is provided with an open end 4 serving as an inlet through which cooling fluid may be admitted. This cooling fluid flows completely down one side of the inner portion, across the bottom, and up the opposite side in the direction indicated by the arrows. By means of a return bend 5 it is conducted downwardly through the outer portion, across the bottom, and then upwardly on the opposite side to the outlet 6.

It will be apparent to those skilled in the art that the entire seat structure may be formed from a continuous length of pipe, or may be formed from any desired number of sections suitably joined together. In order, however, to maintain an internal diameter as nearly constant as possible, I preferably use a construction as illustrated in detail in Figure 1, in which the entire bottom half of the seat comprises a separable section welded to the upper section at each of the points W. This welding is conveniently accomplished by tapering the adjacent ends of the tube, as indicated in Figure 1, whereby a seat for the building up of the welding material is provided.

In like manner, the return bend is preferably welded in position in a similar manner, as will likewise be apparent from Figure 1. This welding of the parts is preferable to the use of couplings, for the reason that it keeps a smooth inside wall as well as a flow path of substantially constant cross sectional area. This in turn insures a substantially uniform velocity of the fluid flow.

For maintaining the inner and outer portions of the seat in properly spaced relation-

ship, there may be provided spacers 7 at any desired number of points, one arrangement of which is illustrated in the drawings. In accordance with this embodiment a spacer is 5 provided adjacent each welded joint to assist in reinforcing the same.

In Figure 3 the seat is illustrated in inclined position across a sewer or other conduit S, a gate valve being illustrated in co- 10 operative relation thereto and in partial conduit-closing position.

It will be understood that the seat having been formed in any desired manner, either from sections or from a continuous piece of 15 material, and by means either of welding or coupling, the space between the inner and outer portions may be filled with suitable fire resisting material preferably of a refractory nature, and conveniently in the form of 20 bricks adapted to lie substantially flush at least with the seating surface of the pipes forming the seat.

Not only does a construction of the character herein described insure uniform flow 25 velocity of the cooling medium with a consequent minimum deposit of any foreign material, but it provides relatively small surfaces. While small surfaces are not as desirable from the standpoint of heat transfer 30 as are large surfaces such as would be provided by seats such as formed from plates, they are decidedly more advantageous than large surfaces from the standpoint of possible difficulties of operation. It sometimes 35 happens, for example, that there is a temporary cessation of the supply of cooling medium. In such cases it is obvious that the metallic parts necessarily soon run dry. Thereafter, the supply of cooling water may 40 be resumed, and the cooled water brought into contact with the heated metal which defines the cooling chamber. This sudden contact between the cool water and the hot metal causes the water to explode or flash 45 into steam, with the consequent generation of tremendous pressures sufficient in many cases to break not only the gate seat and its associated parts, but also the gate itself and the refractory work adjacent thereto. While 50 this obviously requires at least a temporary shut down, such shut downs are of minor importance compared to the possible loss of life of workmen employed on or about the furnace. By the use of a relatively small 55 surface of the character herein illustrated, it will be apparent that the possibility of such an explosion is minimized.

The construction is also highly desirable 60 from the standpoint of the type of cooling which is effected. It will be apparent that at the inlet 4, for example, there is the coolest water, while at the outlet 6 there is the hottest water. Assuming incoming water at a temperature of 70° and outgoing water at 65 a temperature, merely by way of example, of

210°, there is provided an average temperature between the inner and outer portions of approximately 140°. This average temperature exists throughout the entire seat structure inasmuch as at all portions the relatively hotter section is balanced by the relatively cooler section. At the return bend itself, the water in both sections is at substantially the average temperature so that the same condition is true at this point also. Thus there is secured substantially uniform cooling throughout the entire periphery of the seat. This is highly desirable from the standpoint of maintaining a true seating surface.

Many of the same advantages are obtainable with the form of my invention illustrated in Figure 4, in which figure parts corresponding to parts already described are designated by the same reference characters having a prime affixed thereto. This form of the invention is especially adaptable where it is desired to provide a seat for round conduits. As illustrated, the seat comprises a continuous length of pipe shaped to provide an inlet 4' with an outlet 6'. The intermediate portions of the pipe are shaped to provide an outer loop 3' and an inner loop 2', spacing means 7' being provided at suitable points as desired.

At the point 8 where the two loops pass over each other, the pipe is offset, as illustrated in the drawings, whereby the major portions of the opposite side of the seat from that viewed in Figure 4 will all lie in a substantially common plane.

While in all cases the inner and outer loops are preferred, due to the fact that they afford an increased bearing surface for a valve and also define a zone in which refractory material may be located, it will be apparent that some of the advantages of the invention may be obtained by the use of a single loop only.

While I have herein referred specifically to an open hearth sewer, and to a valve seat for use in connection with such sewer, it will be understood that the utility of the invention is not limited with respect to its particular manner of use, but that changes may be made in the construction, use and operation thereof without departing either from the spirit of the invention or the scope of the appended claims.

I claim:

1. As an article of manufacture, a seat comprising a pair of water cooled portions extending in adjacent freely spaced relationship throughout the major portion of their length and lying in a substantially common plane throughout the major portion of their length, said water cooled portions being adapted to be directly engaged by a valve.

2. As an article of manufacture, a seat comprising a pair of water cooled portions extending in adjacent freely spaced relation-

- ship throughout the major portion of their length and lying in a substantially common plane throughout the major portion of their length, and separated spacing means for said members.
3. As an article of manufacture, a seat comprising an inner looped portion, an outer looped portion lying substantially in the plane thereof, but freely spaced therefrom through an air gap, and means for water cooling both of said members.
4. As an article of manufacture, a seat comprising an inner looped portion, an outer looped portion lying substantially in the plane thereof but freely spaced therefrom through an air gap, and means for water cooling both of said members, said members being interconnected at a common point to provide a continuous flow path for cooling medium therethrough, and being adapted to directly engage a valve.
5. As an article of manufacture, a seat comprising an inner looped portion, an outer looped portion lying substantially in the plane thereof but freely spaced therefrom through an air gap, and means for water cooling both of said members, there being separated spacing means for maintaining said inner and outer members in predetermined spaced relation.
6. As an article of manufacture, a seat comprising a substantially paddle shaped inner member, a substantially paddle shaped outer member, said members having the paddle portions thereof lying in a substantially common plane and being disconnected throughout the major portions of their lengths, and means for water cooling said members.
7. As an article of manufacture, a seat comprising a substantially paddle shaped inner member, a substantially paddle shaped outer member, said members having the paddle portions thereof lying in a substantially common plane, and means for water cooling said members, there being separated means for maintaining said members in predetermined spaced relationship.
8. As an article of manufacture, a seat comprising a substantially paddle shaped inner member, a substantially paddle shaped outer member, said members having the paddle portions thereof freely spaced one from the other and lying in a substantially common plane, and means for water cooling said members, each of said members comprising a plurality of sections in end to end welded relationship.
9. As an article of manufacture, a seat comprising a substantially paddle shaped inner member, a substantially paddle shaped outer member, said members having the paddle portions thereof freely spaced one from the other and lying in a substantially common plane, and means for water cooling said members, each of said members comprising a plurality of sections joined together to maintain a flow path of substantially constant cross sectional area therethrough.
10. As an article of manufacture, a seat comprising an inner pipe member, an outer pipe member lying substantially in the plane thereof, but spaced from the inner pipe member throughout its entire periphery, and separated spacing means intermediate said members and lying substantially in the plane thereof.
11. As an article of manufacture, a seat comprising an inner pipe member, an outer pipe member lying substantially in the plane thereof, but spaced from the inner pipe member throughout its entire periphery, and spacing means intermediate said members and lying substantially in the plane thereof, said members each comprising a plurality of sections with separated spacing means located adjacent the points of connection of the respective sections.
- In testimony whereof I have hereunto set my hand.
